UNITED STATES PATENT OFFICE

115,512

DESIGN FOR A MUSICAL INSTRUMENT FOR PLAYING BUGLE CALLS OR THE LIKE

Charles E. Barber, Chicago, Ill., assignor to Chicago Musical Instrument Company, Chicago, Ill., a corporation of Illinois

Application April 17, 1939, Serial No. 84,346

Term of patent 14 years

To all whom it may concern:

Be it known that I, Charles E. Barber, a citizen of the United States, residing at Chicago, in the county of Cook and State of Illinois, have invented a new, original, and ornamental Design for a Musical Instrument for Playing Bugle Calls or the like, of which the following is a specification, reference being had to the accompanying drawing, forming part thereof.

In the drawing:

Fig. 1 is a side elevational view of a musical instrument for playing bugle calls or the like, showing my new design.

Fig. 2 is a top plan view of the same.

Figs. 3 and 4 are opposite end elevational views thereof.

I claim:

The ornamental design for a musical instrument for playing bugle calls or the like, as shown.

CHARLES E. BARBER.
